ELISHA GRAY, OF CLEVELAND, OHIO

Letters Patent No. 76,748, dated April 14, 1868.

IMPROVEMENT IN TELEGRAPH-APPARATUS.

The Schedule referred to in these Letters Patent and making part of the same.

TO ALL WHOM IT MAY CONCERN:

Be it known that I, ELISHA GRAY, of Cleveland, in the county of Cuyahoga, and State of Ohio, have invented certain new and useful Improvements in Telegraph-Apparatus; and I do hereby declare that the following is a full and complete description of the same, reference being had to the accompanying drawings, making part of this specification, in which—

Figure 1, plate 1, is a top view of the relay.

Figure 2 is a side view.

Figure 3 an end view.

Figure 4, plate 2, is a top view of the induction-apparatus.

Figure 5 is a side view of the same.

Figure 6 is an end view.

Figure 7, plate 3, shows the relative position of the relay and induction-apparatus to each other.

Like letters of reference refer to like parts in the different views presented.

The nature of my invention relates to the use of an induction-apparatus in connection with a relay at each office, and the use of an induction to-and-fro current to operate the relay instead of the direct or battery-current.

In order to fully understand the nature of this invention, its application, and great advantage, a brief statement will be made of some of the difficulties incident to the machine now in general use, and which difficulties this invention is intended to overcome.

It is well known that the relays now in use, when operating under heavy escapes or currents of varying intensity, require the most careful and frequent adjustment, and that owing to the difficulty and delays attending such adjustment, it is not unfrequently the case that business is embarrassed, and often wholly interrupted. Each relay, when the line is working badly, may require a different adjustment for each office, and the consequence is that the operators at such times are constantly interfering with each other. From this cause, business being retarded, accumulates to such an extent that it is necessary to have at hand extra operating-force to dispatch it.

In order to obviate these and other difficulties, and cause the relay to act more freely, and independently of escapes and atmospheric disturbances, this self-adjusting or automatic relay is introduced, and is constructed and operated in the following manner, viz:

A, fig. 4, plate 2, is a base, upon which is mounted an induction-apparatus, B C, and B' C' are two relay-magnets, which may be constructed in the ordinary way, except that the magnets need not contain the usual quantity of wire. These two magnets are placed in the line or battery-circuit, and are connected together so that their polarity will be opposite when facing each other.

D D' are two straight magnets wound with wire of such size as will produce the best effect. I have used successfully No. 19, (coarse wire.). Instead of wire, copper ribbon may be used for these magnets, insulated, and connected in the same manner as the coarse wire. One or more coils of the secondary wire or ribbon, whether coarse or fine, may be wound on the magnets B C and B' C', being careful to connect them in the same circuit with the coils of the magnets D D'. In this way a compound induction may be had, one from magnetism alone, the other from the battery-current in connection with the magnetism developed by it.

I do not confine myself to any particular mode of procuring an induced current when the same is to be employed in combination with a primary current for the purposes herein described.

The wires of the magnets D D' are connected together by their inner ends a, while their outer ends b connect with the binding-posts E E'. The poles of magnet D are placed between and in contact with the poles B B'. In like manner the poles of magnet D' are between and in contact with the poles C C'.

The whole apparatus is clamped together by the rod F, and secured to the base by the stays G, fig. 5, plate 2. The rod F may be dispensed with by making continuous cores through the magnets, but preserving

the same connections between the wires. Instead of solid-iron cores, bundles of soft-iron wire may be used with better effect.

The relay referred to and shown in plate 1, is the same in its combination as that described in my patent issued October 1, 1867, excepting that it is very much smaller and the magnets are wound with coarse wire, so as to be used with a quantity-current on a short circuit. I, fig. 1, plate 1, is a base, upon which is mounted the relay, consisting of the magnets J J', supported by the posts K, fig. 2. These magnets are made in the ordinary form of relay-magnets. L is a permanent magnet, and takes the place of the ordinary soft-iron armature. It is secured to the armature-lever M, mounted on a horizontal axis with two pivots C. The poles of the permanent magnet L vibrate between the poles of the magnets J J', which are connected in the same circuit under the base by the wire d. The magnets J J' are so connected that when a current is passing through them, one will repel while the other will attract the permanent magnet L, and thus the three magnets will act conjointly to throw the armature in one direction. By a reversal of the current, the three forces will operate to throw the armature in the opposite direction. Thus, in the former instance, if J were the attracting force and J' the repelling, in the latter, J' would become the attracting force and J the repelling.

These machines may be placed on separate bases, as shown in plate 3, or both may be placed upon the same base, still preserving the same connections.

The operation of this apparatus is as follows: When the line-current is closed, or any part of it, by any key on the line, it passes through the coils of magnets B C and B' C', rendering their cores magnetic. These, by induction, magnetize the cores D D', which induces a momentary current of electricity in the coils around them. This current passes through the magnets J J' of the relay, which is placed in the circuit of the secondary or induced current. The circuit of the secondary or induced current is as follows: Starting from magnet D, it passes through the wire b, binding posts E and N, magnets J J' binding posts N E' to magnet D', which is connected with the magnet D by the wire d. Inasmuch as an induced-current is a to-and-fro current, running in one direction, when the primary or battery-current is closed, wholly or partially, and in the opposite direction when it opens wholly or partially, and inasmuch as the above-described relay works by a reversible or to-and-fro current, it is plain that as often as the battery-current is closed by any key, the relay-armature will move in one direction, and as often as it is opened, the armature will move in the opposite direction.

The advantages of this apparatus are numerous, a few of which will be named. The relay is self-adjusting. Working on the principle it does, it is impossible for it to be otherwise. For this reason it will effect a great saving in operating-force at the head offices. It will work through all kinds of weather without adjustment, and with very much less battery-power, owing to the delicate construction and peculiar combination of the relay, thus rendering it possible and easy to do a given amount of business with a less number of lines, less battery-power, and a less number of operators.

By this apparatus a line is rendered available for use at all times, and for this reason will much better and more economically subserve the wants of the public.

Another mode of constructing a relay which may be worked by induced electricity, consists of an electro-magnet made in the ordinary way, except that the wires of the spools are so connected as to develop similar polarity at each end of the core, and an opposite polarity in the middle or end of the magnet, thus making a magnet of three poles, or it may be considered as two magnets in one core. This magnet is placed horizontally upon a base, so that one spool or limb of the magnet is directly above the other.

The armature is a straight piece of steel, magnetized, and long enough to reach from one pole or from one limb to the other. It is pivoted in the middle, and operated by an induced to-and-fro current. Inasmuch as the armature is a magnet having a north pole at one end and a south pole at the other, and as the ends of the cores of the before-mentioned electro-magnets are either both north or both south poles, it follows, the armature being hung in the middle, that when a current is passed through the wires of the electro-magnet, one end of the armature will be attracted while the other will be repelled, so that as often as the current is reversed through the magnet or magnets, the armature will vibrate.

What I claim as my invention, and desire to secure by Letters Patent, is—

1. I claim operating a relay by to-and-fro currents of magneto-electricity, momentarily induced by a disturbance of the main or line-current, in the manner substantially as described.
2. In combination with the receiving-magnet or magnets, I claim the electro-magnetic armature, in which a secondary current is induced on the disturbance of the line-current, substantially as described.
3. In combination with the induction-apparatus, constructed as described, I claim the polarized relay, placed in a short circuit, and operated by induced currents, in the manner and for the purpose as set forth.
4. I claim the arrangement of the magnets B C and B' C', in combination with the magnets D' D', used in the manner and for the purposes substantially as described.

ELISHA GRAY.
